ELECTRIC WATER PUMP

Linus E. Russell, Springfield, Ohio, assignor to Peters & Russell, Inc., Springfield, Ohio, a corporation of Ohio

Filed Jan. 5, 1962, Ser. No. 68,205

Term of patent 14 years

(Cl. D65—1)

FIG. 1 is a perspective view of an electric water pump embodying my new design;

FIG. 2 is a perspective view of the opposite side thereof; and

FIG. 3 is a rear elevational view thereof.

I claim:

The ornamental design for an electric water pump, substantially as shown.
